DEVICE FOR PLAYING A WORD GAME

Felix Gilbert, New York, N.Y., assignor to De Luxe
Reading Corporation, a corporation of New Jersey

Filed Mar. 1, 1966, Ser. No. 1,226

Term of patent 7 years

(Cl. D34—5)

FIG. 3

FIG. 4

FIG. 5

FIG. 6

FIG. 7

FIG. 1 is a left side elevational view of a device for playing a word game showing the new design;

FIG. 2 is a top view looking in the direction of the arrows 2—2 of FIG. 1;

FIG. 3 is a right side elevational view of the device;

FIG. 4 is a front view looking in the direction of the arrows 4—4 of FIG. 1 with portions omitted for convenience of illustration;

FIG. 5 is a rear view looking in the direction of the arrows 5—5 of FIG. 1;

FIG. 6 is a bottom plan view; and

FIG. 7 is a horizontal cross-sectional view taken on line 7—7 of FIG. 2.

The essential features of my design reside in the portions shown in full lines.

I claim:

The ornamental design for a device for playing a word game, as shown and described.
